Primary Examiner — Marianne N Pandozzi*Assistant Examiner* — Jae Liang(57) **CLAIM**

The ornamental design for a stemmed glass set, as shown and described.

DESCRIPTION

FIG. 1 is a left perspective view of a first embodiment of a stemmed glass set showing my new design;

FIG. 2 is a top view thereof;

FIG. 3 is a bottom view thereof;

FIG. 4 is a right side view thereof, the left side view being a mirror image thereof;

FIG. 5 is a front view thereof;

FIG. 6 is a rear view thereof;

FIG. 7 is left perspective view of a second embodiment of a stemmed glass set;

FIG. 8 is a right side view thereof, the left side view being a mirror image thereof;

FIG. 9 is a front view thereof; and,

FIG. 10 is a rear view thereof.

The broken lines in the drawings depict portions of the stemmed glass set that form no part of the claimed design.

1 Claim, 3 Drawing Sheets(56)
